mesne assignments, to Graham & Barker,
Ridgewood, N. J., a limited partnership

Original application November 30, 1939, Serial
No. 306,797. Divided and this application
March 2, 1946, Serial No. 651,497

2 Claims. (Cl. 68—174)

1

My invention relates to washing machines or devices, exemplified herein as applied for household laundry purposes, and more particularly to improvements in such machines.

This application is a division of my copending application for Washing Machines, Serial No. 306,797, filed November 30, 1939, now Patent No. 2,407,660, issued September 17, 1946.

An object of the invention is to provide novel circulation of water, and novel movement of clothes, in a washing machine, whereby to effect better interchange of position of the water and clothes to ensure effective cleaning.

Other objects of the invention are the provision of novel agitator or baffle means, particular water connections, and other elements.

Another object of the invention is to provide a washing machine of the above indicated character that is simple and durable in construction, economical to manufacture and effective in its operation.

Another object of the invention is to provide a novel resilient or shock-absorbing means for a power unit of a washing machine, exemplified as of the oscillating type.

With such objects in view, as well as other advantages which may be incident to a utilization of the improvements, individually or in combination, the invention comprises the elements and combinations thereof herein set forth and claimed, with the understanding that the several necessary elements constituting the same may be varied in proportion, arrangement and texture, without departing from the spirit and scope of the invention as intended, and as set forth in the drawings, specification and claims.

In order to render the invention more clearly understood, means are shown in the accompanying drawings for carrying the invention into practical effect, without limiting the improvements to the particular elements shown and described, which for the purpose of explanation, are made the subject of illustration.

In the drawings:

Figure 1 is a front side view, partially in elevation and partially in substantially central vertical-plane section, of a washing machine of a particular type constructed in accordance with the invention;

Fig. 2 is a view showing a fragmentary detail of an upper agitator or baffle element, as viewed in the direction of an arrow 2 of Fig. 1;

Fig. 3 is a sectional view, taken along the line 3—3 of Fig. 2;

Fig. 4 is a sectional view, taken substantially along the line 4—4 of Fig. 1;

2

Fig. 5 is an enlarged top plan view of an agitator and a lower portion of a tub; and

Fig. 6 is a sectional view of the structure of Fig. 5.

Referring particularly to Fig. 1, the example of the machine therein illustrated comprises a lower base 26, an upper stationary housing 27 on the base 26, an oscillatory tub 28 disposed generally in the housing 27, top or lid construction 31 extending above the housing, an agitator 33 having baffle elements or means 32 at the bottom of the tub, and baffles 34 near the top of the tub, for agitating the clothes and water in the tub during washing, flushing, and rinsing actions, a diaphragm 33 in the tub for effecting flushing and drying actions by expansion of the diaphragm, a valve 36 under the tub for admitting fluid behind the diaphragm and in part controlling operation of the diaphragm 33, a power, or tub oscillating, unit assembly 41 supported by the base 26 under the housing 27, and shock absorbing suspension means 42 for the power unit 41 associated therewith. An automatic control mechanism (not shown) also is mounted on one side of the housing 27.

The base structure 26, which may be any one of several different types for supporting the other parts and causing the top of the machine to have a certain convenient level suitable to the average user, has legs 51, at least two of which, as seen in Fig. 1, are suitable in location and construction for cooperation with the shock absorbing suspension means 42, as will later be described. The legs 51 are, in this instance, of pressed metal having channel section, joined at the lower ends, as by tie rods 53, and suitably supporting, at the tops, a metal or other disc or plate 56, preferably by means (not shown) for detachably mounting the legs in position. Castors 54 of the swivel type on the legs 51 or other means, may be provided for the easy movement of the machine from one position to another on a floor, in a usual manner.

The plate 56, in this instance, is surmounted by a shell or ring 57 of thin pressed sheet metal having a horizontal peripheral top flange 58 for attachment to the housing 27, and a peripheral bottom flange 61 telescoping and suitably held to the plate 56.

The housing 27 encloses the tub 28, and other parts, and receives wash and rinse water ejected from the top of the tub, as will later appear. A pipe 62, extending from the bottom of the housing through the plate 56, is provided for draining the housing 27. The housing comprises a thin sheet metal lower cup like portion 63, having an upper vertical peripheral flange 68 to

which is secured an upper thin sheet metal cylindrical member 71. At its upper end, the cylinder 71 is provided with an annular thin sheet metal shell or cap 72 having an offset perimeter 73 secured to the top periphery of the cylinder 71. The remainder of the cap 72 is of substantially half round section, forming a relatively large upwardly convex bead or toroid, having a relatively small, radially inwardly extending flange 77 about the upper part of the tub 28 and in closely spaced relation thereto. A bushing 78 is provided in an opening in the shell 72, for a purpose to be hereinafter set forth.

The tub 28 is of the oscillating type for operation about a vertical axis, relative to which its sheet metal body 79 is of somewhat elongated globe shape having a clothes receiving opening at its top, and being shaped, at its upper and lower portions, for the reception of, and cooperation with, baffle elements of agitator means, which will be later described. The tub has a somewhat hemispherical or bowl shaped bottom portion 79' and an inverted, somewhat hemispherical top portion 79'', the sides of these portions forming parts of the side walls of the tub and are joined together by a substantially straight side wall portion 79'''.

The tub has a portion 81 pressed upwardly at the tub bottom (Figs. 1 and 6). A disc-like metal mounting element 82 is provided outside the tub bottom, and the agitator 83, having a disc-like base 84, is provided inside the tub bottom, these elements extending about the portion 81 and conforming to and being secured to the tub, as by rivets.

The bottom mounting 82 has a recess for the reception of the upper end of a drive shaft 87 which is operatively connected to the mounting 82, this connection being indicated by a pin 88. The lower portion of the tub also communicates, through a bushing 89, with the valve 36, for controlling the diaphragm movements as will be further set forth.

At about its vertical central portion the tub 28 is provided with a peripheral channel 92, Fig. 1, open at the inner side of the tub and constituting part of means for attaching the diaphragm 33 to the tub, as will further appear.

The top of the tub has secured thereto a metal casting or neck portion 96, of cylindrical or ring-like character, having a depending tapered flange 97 conforming, at its outer surface, to the inner surface of the sheet metal body 79 of the tub, and having its inner surface gradually merging and curving into the curved inner surface of the sheet metal body whereby to preserve the gradually rounded inner top contour of the tub. The neck portion of the casting 96 has an outwardly projecting peripheral flange 102, in which is a top groove 103. A plurality of peripherally spaced ducts or outlet ports 106 extend diagonally downwardly and outwardly through the casting 96 from the groove 103 to the exterior of the tub, for allowing water from the tub to drain into the housing 27 through the radially narrow peripheral space between the flange 77 on the shell 72 and the upper part of the sheet metal tub.

A plate-like element 111 of the lid 31 is constructed of sheet metal pressed to inverted shallow substantially dish shape. The metal of the plate at its periphery encircles a ring 113, in this instance, of square cross section, which forms a flange that overlies and cooperates with the flange 102. Mounted concentrically with the

ring 113 is a frame 132 between which and the plate 111 is disposed a rigid screen 133 conforming in general to the shape of the plate 111. The frame 132 is appropriately secured to the plate and has peripherally spaced, downwardly extending ducts 134 which communicate at their lower ends with the peripheral groove 103 and at their upper ends with the screen openings.

The screen 133 is of large mesh and also has radial top grooves or corrugations 135 which, when the clothes mass is pressed against the screen by the diaphragm, form gutters or channels for better draining off the water outwardly through the space between the ring 132 and plate 111, downwardly through the ducts 134 into the top annular groove 103, and thence through the ducts 106, into the housing 27, as above mentioned. Before the clothes are tightly pressed against the screen, the main bulk of the wash or rinse water being displaced by the diaphragm flows freely outwardly through various parts of the screen, irrespective of the grooves 135, thence into the ducts 134 and outwardly from the tub as stated. Although the drawings show the ducts 106 and 134 substantially in register, the groove 103 and the ducts 106 may be of sufficient capacity to carry off the water admitted to the groove by the ducts 134 irrespective of the locations of the latter around the groove.

The lid 31 is removably held upon the tub by a clamping ring 117 of channel section, which embraces the lid flange 113 and the tub flange 102, when the lid is in place on the tub. The ring is split, as at one position about its periphery and provided with operating means for peripheral expansion of the clamping ring to release the lid for opening, and for peripheral contraction of the ring for locking the lid in closed position.

At the top outside center of the lid 31, an aperture therein is surrounded by a nipple 136 (Fig. 1) attached thereto, on which is a grooved ferrule 137. A cap like member 138 has rotative water sealed relation to the nipple, being provided with a spring clip 143, the inner end of which removably extends through an opening in the cap and into the groove of the ferrule. The cap 138 is connected, by a coupling 139, to a flexible conduit 140 of the metal armored type. The conduit extends through the bushing 78, and between the housing 27 and the tub 28, to a nipple 141 in the bottom wall of the housing. Water is supplied to the conduit 140 from an inlet connection 142, secured to the bottom disc 56, through a hose or conduit 144, which extends through an opening in the shell 57, to a valve of an automatic control mechanism (not shown), and from the valve through a hose or conduit 149, extending through an opening in the shell 57, to the nipple 141, to which the conduit 140 is connected. A source of heated water may be connected to the inlet 142.

A section 151 of the flexible armored conduit 140 (Fig. 1) operates as a hinge, or flexible mechanical connector, between the housing 27 and the lid 31, to prevent complete separation of the lid from the tub when the lid is open, and to hold the lid in convenient position for closing the tub. Also, the section 151 of the conduit 140, may move back and forth through the bushing 78 to avoid buckling of the conduit and to better control the action of opening and closing the tub.

Although agitation or stirring of the clothes

and water may be obtained by agitating means operating relative to a stationary tub, in the example here given it is obtained by baffles fixed to the oscillating tub whereby the water and clothes are given a special tumbling action during washing, substantially as indicated by arrows D; and, during rinsing, combined with, or augmented by, the action of fresh incoming water in the direction of an arrow E, shown at the top of Fig. 1. Either or both sets of baffles 32 and 34 may be employed in either operation, and either or both may be formed in the tub by being pressed therein.

The upper baffles 34 are herein shown as integral parts of the top metal casting 96, although they may be separately attached thereto, or to the tub, or constitute parts of the tub body as indicated, and may be varied in number, two being shown, located at opposite sides of the tub. They are, as better illustrated in Figs. 2 and 3, of fin-like character rounded at the inner thinner edges 156, and each having a tapered side 157 merging gradually into the inner surface of the tub body, while the opposite side 158 of each baffle is straight, presenting a flat, radially extending side. The flat sides of the baffles 34 face in the same direction with respect to the direction of tub oscillation, for a purpose to be referred to later. The edges 156 slope downwardly and inwardly from the casting 96, substantially as chords of the cross sectional arc of the tub body 79, to a position close to the mid channel 92, where they are suddenly sloped into the tub surface.

The broad sides of the baffles extend in a general radial direction to the tub axis at any horizontal section, but are inclined upwardly, and, longitudinally, they slope relative to the vertical at an angle of about twenty-five degrees, as better seen in Fig. 2. The cross section of each of these baffles is substantially as shown in Fig. 3, the apparent thicker section thereof indicated in Fig. 1, being caused by the vertical cut therethrough along the line 1-1 of Fig. 2. These baffles slope oppositely, so that this section also requires that the upper part of the left hand baffle, and the lower part of the right hand baffle, as viewed in Fig. 1, be shown in full lines, and that the lower part of the left hand baffle and the upper part of the right hand baffle be shown in dot and dash lines, since looking into the baffles along the line 1-1 of Fig. 2, as is actually the case in Fig. 1, would only show the upper part of the left hand baffle, and the lower part of the right hand baffle, as will be understood.

The lower agitator 83 (Figs. 1, 4, 5 and 6) comprises the dish-like base 84, on which the baffles 32 extend radially from the center. At the upper edge the baffles are rounded, and the sides divergently taper to the base. In vertical plane outline, each baffle 32 is of generally curved or rounded contour conforming somewhat to the lower recess of the tub, and has an outer enlarged portion 163. The baffles 32, in relation to such recess and to the globular sides of the outer portions of the tub, cause the water and clothes mass to be impelled radially outwardly and upwardly along the sides of the tub, which mass if uninterrupted, would immediately move downwardly in the center of the tub, round and round. However, at the top the clothes encounter the additional agitation produced by the upper baffles 34, which will break up the cycle produced by the lower agitator, and keep the clothes well spread out in the water so that all clothes receive

the full agitation, which is a combination of actions.

The baffles 34, by the length and the angular disposition thereof, tend to and do lift the clothes along the baffles, and toward the center of the tub, and to turn the clothes over. The baffles are of greatest radial depth midway of the length thereof so that as the tub oscillates on its vertical axis, the greatest force exerted upon the clothes is radially inwardly along and opposite these mid-sections. However, the sections of the baffles 34, above the mid-portions, exert a more or less downward component of movement toward and along the axis of the tub, and the sections of the baffles, below the mid-portions, exert a thrust radially inwardly. The result of all of these forces is to cause considerable agitation of the clothes in the upper portion of the tub as they are moved inwardly, and before they are carried downwardly in the center to be again subjected to the action of the lower agitator.

During rinsing, the central downward movement is augmented by the fresh rinse water entering the tub, in the direction of the arrow E. At the same time, the fresh water is introduced and mixed in definite and symmetrical manner, ensuring its diffusion to all parts of the clothes mass, and avoiding rinsing more at one part than at another, as will appear.

In addition to the described actions of the upper baffles 34, they perform a further function in augmenting the thorough cleansing action on the entire clothes mass. Since the tub oscillates on a vertical axis, and the baffles have flat sides facing in the same direction, as these flat sides move forwardly, they produce a different agitation from the broad sides or faces and also engage the clothes mass and move it part way around the tub circumferentially to occupy a different position with respect to the main forces exerted by the baffles. As the baffles 34 move in the reverse direction the clothes mass slides off the slanting faces thereof. The next forward motion of the flat sides of the baffles engages a different portion of the clothes mass, and thus the clothes are moved around the vertical axis with a step by step motion, in addition to all the other movements imparted thereto.

The power unit herein described is the main drive motor and mechanism for oscillating the tub to agitate the clothes. The drive shaft 87 (Fig. 1) is journaled in a relatively long sleeve bearing 231 having exterior screw threads, whereby it is vertically adjustably mounted in tubular post 232, and it is fixed in adjusted position by a nut 233. The post 232 has a top flange bolted to the bottom 63 of the tub housing 27, and a bottom flange bolted to the bottom disc 56. The drive shaft 87 has a lower portion 241 of reduced diameter providing a shoulder, which rests on a ball bearing 242 that is held in place by a gland 243 through which the shaft portion 241 extends. Below the portion 241, the shaft is of square cross section, which terminates in a threaded end 244. A sleeve 247 of a crank arm 248 (also Fig. 4) fits upon the squared portion of the shaft 87, and is pivotally connected to one end of a link 252. The other end of the link 252 is pivotally connected to a worm wheel 256, the pivotal connection being eccentrically located thereon. A shaft 257, of the worm wheel 256, is mounted in the bottom of a lower casing 261, which also carries a bearing 262 for the sleeve 247. An upper casing 263 has a bearing

264 for the sleeve 241. The casing portions 261 and 263 have cooperating outer flanges 265 secured to each other, as by bolting. This mechanism is supported upon the lower end of the shaft 87, as by a washer 266 and by a nut 267, which is locked in place.

A worm screw 268, on a shaft 269, engages the worm wheel 256, and is driven by a motor 271 through pulleys 272, and a belt 273. The motor 271 is supported on an arm 274, which is pivotally mounted on a projection extending from the upper casing 283. A screw 282, mounted on the casing 261 cooperates with the arm 274 for adjusting the position of the motor on its pivot mounting, to regulate the tension in the belt 273. In operation, when the motor 271 is energized, it causes continuous rotation of the worm wheel 256, which is translated into oscillating motion of the crank arm 248 and consequently, of the drive shaft 87 and the tub 28.

A casing for the drive mechanism comprises an upper shell 286 secured to a lower pan 287, as by bolts 288. The pan 287 is secured to the gear casing 281—263, as by the nut 267 and a nut or nuts 289 on the lower end of shaft 257. The bolts 288 also secure laterally extending plates 291 to the pan at radially opposite parts thereof. The plates 291 are connected to leaf springs 292, of the shock absorber devices 42, which, in turn, are secured to two of the legs 51 of the machine. Near the ends of its strokes, the oscillating structure has its motion damped by the yieldability of the springs 292 in a direction circumferentially of the drive shaft, the springs being rigid in the up and down direction.

The diaphragm 33 hereof is made of high grade durable soft rubber or other material, and is molded or formed such that, in its contracted or relaxed state, it not only conforms closely to the shape of the tub, but also to the agitator baffles 32, and to other parts of the lower agitator 83.

The diaphragm is somewhat semi-spherical in shape, having an upper edge peripheral bead 167, Fig. 1. An expansion ring 171 engages the upper peripheral part of the diaphragm, just under the bead 167, pressing the same into the channel 92 formed in the tub side wall to mount the diaphragm with a water-tight connection to the tub.

At its bottom, the diaphragm is further provided with portions 168 of inverted substantially channel section closely conforming to, and in relaxed condition fitting over the baffles 32. During expansion, the diaphragm lifts off the bottom of the tub, rising from the baffles and, since it does not turn relative to the tub, returns easily and accurately to position fitting the baffles. The flow of water to and from the space between the diaphragm 33 and the bottom of the tub, to expand and contract the diaphragm, is controlled in part by the diaphragm valve 36, indicated in Fig. 1, water under pressure being admitted by the valve 36 through the bushing 89 to position under or behind the diaphragm, to push or expand the diaphragm upwardly in the tub.

As the clothes are compressed between the diaphragm and the screen 133, the wash or rinse water escapes from the top of the tub, as above described. Near the end of the drying operation, the pressure behind the diaphragm builds up to that of the incoming fluid. When the water supply has been stopped by the aforesaid automatic control mechanism, a bleeder valve of the valve 36 allows the water pressure in the valve casing

to drop gradually. After a certain amount of bleeding, the valve 36 opens to the full open position allowing the water behind the diaphragm to flow, aided by contraction of the diaphragm 33, into the bottom of the housing 27, from which it drains through the drain pipe 62. The water pressure applied behind the diaphragm during expansion of the latter being substantially uniform, the pressure developed in the drying and flushing operations are readily calculable, so that the valve 36 may be properly adjusted to effect the desired draining, quickly and in proper sequence.

The pressure maintained by the adjustable bleeder of the valve 36 also enables regulating the duration of the time period of high pressures on the clothes, that is to say, the rate of bleeding can be adjusted to determine the length of time before the valve 36 opens to dump the water from behind the diaphragm and, therefore, there may be a period of sustained higher pressures during the drying operation.

The water supply to the diaphragm valve 36 is from an inlet pipe 211 (Fig. 1), secured to the disc 56 by a clip 212, through a conduit 216, which extends through an opening in the shell 57, to a valve of the automatic control mechanism. From the latter valve, the water is conducted through a conduit 181, which enters the shell 57 and extends upwardly through a nipple 226, in the bottom wall of the housing 27, whereupon it is formed into a flat spiral section 227, of about two turns, surrounding the drive shaft 87, before connecting to the diaphragm valve 36.

Special provisions are made to insure complete draining of the water from behind the diaphragm 33, and to insure against accidental and premature closing of the opening to the diaphragm valve. To this end, the lower face of the base 84 of the lower agitator has an annular groove 228, Figs. 1 and 6, leaving a peripheral portion 229. The head of the mounting bushing 89 for the diaphragm valve 36 is received in the groove 228. The base 84 has apertures 234 therethrough communicating with the groove 228, and the peripheral portion 229 has apertures 232 also communicating with the groove 228. When water is admitted behind the diaphragm, it passes through the apertures 234 and 232 to start the diaphragm expansion. When water is being expelled from below the diaphragm, it drains through the apertures 234 and 232 into the groove 228 and from the latter through the valve 36 to the tub housing 27, but without danger of the diaphragm fouling the opening into the diaphragm valve 36.

Operation

At the beginning of the operation of the machine the operator places the dry clothes in the tub. The machine is next filled with water and soap, washing powder or water softener added, after which the lid 31 is locked in place.

The motor is started which oscillates the tub 27 and agitation of the clothing and water as well as circulation of the clothes is produced as described above. At the end of a selected washing period, the control mechanism may operate to admit water behind the diaphragm 33, through the valve 36, to a flushing operation in this case, in which the diaphragm lifts the clothes and wash water toward the top of the machine, so that the wash water is gradually forced out through the drain openings 134, in the lid, and 106 in the tub. Thus, any scum and matter,

which has accumulated on top of the wash water, is flushed out of the machine. At this time, the agitation of the machine has not been stopped. It may be stopped when the diaphragm has lifted the clothes and water past the center of the tub, which is about one-half or two-thirds of the flushing cycle, so that agitation continues, by means of the upper baffles, whereby the accumulated matter also is liberated from the clothes to float off with the water.

Inflation of the diaphragm may continue, until substantially all of the wash water has been extracted from the clothes, at which time, the valve 36 operates to empty the water from behind the diaphragm, and the diaphragm returns to its lower position shown in Fig. 1.

By this time, the control mechanism has operated to admit water to the tub through the center of the lid, which is the beginning of the rinsing operation. When sufficient water has been admitted to the tub to make agitation of the clothes and water of some benefit, which is about one-third of the time consumed by the rinsing operation, agitation is re-started. Agitation continues during the remainder of the rinsing operation, and for a sufficient length of time for the tub to completely fill with water and also to overflow through the ducts 134 and 106 for a sufficient interval of time to thoroughly rinse the clothes.

At the conclusion of the rinsing operation, the control mechanism again opens the diaphragm water valve, to again expand the diaphragm to eject the rinse water, and this is the beginning of the drying operation. Agitation is continued further, until the diaphragm is above the center of the tub, and preferably during about half of the period of time for this particular operation of the diaphragm. The expansion of the diaphragm continues to bring about drying of the clothes by compressing the same against the upper portions of the tub and its cover, until substantially all of the water is extracted from the clothes whereupon the supply of water behind the diaphragm is shut off, and the action of the diaphragm valve 36 will again operate to dump the water from behind the diaphragm.

Other modifications may be made in the arrangement and location of parts within the spirit and scope of my invention, and such modifications are intended to be covered by the appended claims.

I claim:

1. In a washing machine, a tub, means for moving said tub about an upright axis, separated baffle members for agitating the contents of the

tub and respectively located in the regions of said tub above and below the center thereof, a diaphragm mounted in said tub, and means for causing the diaphragm to move the contents of the tub away from the lower baffles whereupon only the upper baffles will be effective to agitate the contents of the tub as the tub is moved.

2. In a washing machine, a tub having an upper access opening, means for oscillating said tub about an upright axis, baffles in said tub for agitating the contents of the tub when it is oscillated, a lid for said opening, a liquid inlet connection to the lid of the tub, said connection comprising a tube mounted on said lid and a cap swivelled upon said tube, and a flexible hose connected to said cap.

GEORGE C. GRAHAM.
